UNITED STATES PATENT OFFICE

GEORGE F. MCGILL, OF MARENGO, ILLINOIS

TELESCOPING AND FOLDING GARMENT HANGER

Application filed August 29, 1928. Serial No. 302,719.

The invention relates to a telescoping and folding garment hanger and has for its object the provision of a hanger which may be compactly folded into a small compass and carried in a pocket, bag, suitcase or other container.

One of the principal objects of the invention is to construct the garment hanger in such a manner that it is extensible and may serve its purpose for garments and apparel of various sizes; in other words, the hanger is provided with slideable arms or extensions which may be telescopically and frictionally held at any place desired in the main casings of the structure.

Another object of the invention is to secure a strong, durable and rigid structure without sacrificing the possibility of extension of the outer arms of the holder to any position desired.

It is another object of the invention to construct the holder of light-weight sheet metal stampings which will be inexpensive to manufacture and which may be readily formed and assembled.

A further object of the invention is to provide the inner end portions of the extension arms which slide in the main casings of the holder with diverging or laterally extending wall portions which are constructed in a manner to make them flexible and resilient and permit them to frictionally engage the inner side walls of the main casings in order to hold the slideable arms at the desired places within the main casings.

In addition, it is an object of the invention to construct the inner end portions of the extension arms with depending walls which are formed to contact with and slide upon inturned bottom wall portions of the main casings in order to increase the frictional resistance and holding qualities of the extension arms and casings, thereby securing with the diverging or laterally extending wall portions double acting means of the inner end portions of the extension arms in connection with holding and maintaining the extension arms in the places desired by the user of the hanger.

An additional object of the invention is to

provide the outer extremities of the extension arms with means whereby the extension arms may be grasped and moved to the places desired within the casings.

Because of the adjustable and extension features of the garment hanger, when partly extended it is especially well adapted for use in hanging infants' and children's clothing, and when fully extended may be used for hanging any garments or apparel.

The invention will be explained and more readily understood when read in conjunction with the accompanying drawings illustrating one embodiment of the invention, but it will be understood that various changes and modifications of which the invention is susceptible may be made without departing from the spirit of the appended claims forming a part hereof.

In the drawings:

Figure 1 is a front elevational view of the folding garment holder, showing the ends of the extension arms protruding from the outer ends of the main casings and showing by dotted lines one of the arms in extended position.

Figure 2 is a top plan view of the holder shown in Figure 1.

Figure 3 is a bottom plan view of the holder shown in Figure 1.

Figure 4 is a sectional view through one of the pivot connections on the line 4—4 of Figure 1.

Figure 5 is a front elevation view showing the holder in folded and compact condition with the extension arms within the main casings.

Figure 6 is a side elevation of the holder as shown in Figure 5.

Figure 7 is a top plan view of the holder as shown in Figure 5.

Figure 8 is a longitudinal sectional view showing principally one of the main casings of the holder and one of the inner extension arms.

Figure 9 is a sectional view on the line 9—9 of Figure 10 and illustrates how the inner end of one of the extension arms diverges and is frictionally held against the inner walls of the outer casing.

Figure 10 is a longitudinal sectional view on the line 10—10 of Figure 9.

Figure 11 is a transverse sectional view on the line 11—11 of Figure 10.

5 Figure 12 is an end elevational view of the inner end of one of the extension arms, showing the flared and divergent portions of the arm, and,

10 Figure 13 is a perspective view of the inner end portion of one of the extension arms.

The garment holder comprises the central body member of metallic frame 15, from opposite sides of which the curved main casing members 16 and 17 extend. The central 15 body frame 15 is formed from a piece of sheet metal which is bent into the shape of a U and comprises the side walls 18 and 19 and the base or bottom wall 20. The exterior corners, where the walls 18 and 19 join with the 20 base 20, are rounded, so that garments which are placed on the hanger shall not be caught on the sharp corners. All of the ends of the side walls 18 and 19 are cut off and rounded at their top corners.

25 Ears or lugs 21 and 22 extend outwardly from the top of the wall 18 of the central body member 15 at the central portion thereof. These lugs have their outer edges rounded so that they will not catch in the garments. They are arranged with a space between to permit the garment hanger hook 23 to be placed in the space. The garment hanger hook 23 is preferably formed of wire of suitable gauge and is secured in the central body member 15. The hook 23 is provided with a shank 24 which shank is held in upright position between the outwardly extending ears or lugs 21 and 22. The hook is thereby prevented from moving laterally and 40 getting out of position with respect to the central body member 15.

The garment hanger hook 23 is provided with the handle portion 25 so that the garment holder may be suspended from a hook, 45 or other support. The shank 24 has a lower right angle portion 26 which is passed through apertures made in the walls 18 and 19 and is riveted or otherwise secured in the wall 19. The shank 24 turns into the right 50 angle portion 26 with a curve so that garments will not be caught and injured.

The curved metallic extension casings 16 and 17 are stampings formed, as shown in the drawings, from single pieces of metal. 55 These casings 16 and 17 also have rounded edges so that the garments and apparel will not be caught on sharp corners. The curved metallic extension casings 16 and 17 are connected to the central body member 15 by means of the metallic pivot rods 27 and 28, respectively, which latter are provided with rounded heads. The pivot rods 27 and 28 are passed through apertures made through the walls 18 and 19, respectively, of the central body portion 15 and also the side walls 65

of the casings 16 and 17, respectively, and are suitably riveted to the side walls 18 and 19 of the body member 15.

Each of the casing members 16 and 17 are provided with side walls 29 and 30, respectively, the top wall 31 and inwardly extending flanges, ledges or run-ways 32 and 33 opposite the top wall 31. The inner lower ends of the side walls 29 and 30 are cut off and rounded.

75 The inwardly extending flanges, ledges or run-ways are separated by the air space 34. The side walls 29 and 30 are parallel, and the top wall 31 and the inwardly extending flanges 32 and 33 are substantially concentric to one another except that at the ends of the inwardly extending flanges, ledges or run-ways 32 and 33 there are up-turned portions 35 and 36 which are used to prevent the extension arms from becoming disengaged 85 from the casings.

The curved metallic extension arms 37 and 38 are stamped from single pieces of metal and formed as shown in the drawings. They are telescopically and frictionally engaged 90 in the interior of the extension members or casings 16 and 17.

95 Each of the extension arms 37 and 38 comprises side walls 39 and 40 and the top wall 41, respectively. The walls 39 and 40 of each of the arms 37 and 38 are provided at their inner portions with notches 42 and 43, respectively. These notches are preferably placed opposite to one another in the side walls 39 and 40 and leave depending wall portions 44 and 45 near the inner ends of the walls 39 and 40, respectively.

100 The notches 42 and 43 are cut in the walls 39 and 40 a sufficient distance from the ends thereof to permit the wall portions 44 and 45 to have their proper flexure in order to perform their functions when in frictional contact with the side walls 29 and 30 of the casing members.

105 The wall portions 46 and 47 of the walls 39 and 40, respectively, on the other side of the notches 42 and 43, have their lower ends extending below the ends of the wall portions 44 and 45. The walls 39 and 40, except for the portions 44 and 45, are parallel. The wall portions 44 and 45 diverge and extend laterally from the top wall 41. The walls 39 and 40 are gradually curved and tapered except that at the wall portions 46 and 47 there are relatively sharp declines toward the inner ends of the arms 37 and 38, as shown particularly in Figure 8.

110 The outer ends of the extension arms 37 and 38 are provided with detents 48 and 49, respectively. These are for the purpose of 115 grasping the extension arms to move them to the places desired in the casings 16 and 17.

The upturned portions 35 and 36 of the inturned flanges or ledges 32 and 33 cause 120 the outer extremities of the casings 16 and 17 125

to be smaller than the inner extremities of the extension arms 37 and 38, so that the extension arms 37 and 38 when arranged at their outermost positions in the casings 16 and 17, will not fall therefrom, nor can they be passed or withdrawn therefrom, but are permanently held in place.

In the center of the lower wall 20 of the central metallic frame 15 at each of the ends thereof, detents 50 and 51 are punched up. The detents fit in the open air spaces 34 between the flanges or ledges 32 and 33 when the casing members 16 and 17 are brought down against the bottom wall 20. The flanges or ledges 32 and 33 rest against the intervening portions of the bottom wall. By this means the casings 16 and 17 are held in snug and firm relationship with the central frame when the casings are in extended position.

As will be seen from the foregoing description of the construction of the garment holder, it may be opened by swinging the casing members 16 and 17 on the pivot rods 27 and 28. In swinging, the casing members are permitted to rotate within the central frame member 15 because the inner lower corners of the side walls 29 and 30 have been rounded.

When the casing members 16 and 17 have been brought down, swinging on the pivot rods 27 and 28 and brought to rest on the bottom wall 20, their tops form a curved surface upon which to hang the garments or apparel.

In case it is desired to have a longer hanger than would be secured by merely extending the casing members 16 and 17, the extensions 37 and 38, which are telescopically secured within the casings 16 and 17, may be fully extended to any desired position, or any intermediate position required to fit the garments to be hung.

It will readily be seen that because of the diverging and flaring of the wall portions 44 and 45 that when the extension arms 37 and 38 are placed within the casings 16 and 17, the wall portions 44 and 45 thereof are in compression. As the extension arms 37 and 38 are moved along the interior of the casings to the positions desired, the wall portions 44 and 45 in frictional contact with the interior faces of the walls 29 and 30 offer resistance which is sufficient to hold and maintain the parts together except as force is applied to separate them.

During the movement of the extension arms 37 and 38, and while the divergent wall portions 44 and 45 are pressing against the interior surfaces of the side walls 29 and 30, the points of the depending wall portions 46 and 47 are riding upon or sliding along the inturned flanges or run-ways 32 and 33.

When the extension arms 37 and 38 have been pushed into the casings 16 and 17 as far as they will go, the inner edges of the arms contact with the pivot rods 27 and 28. When

the extension arms have been pulled out as far as they will go, the downwardly extending edges of the depending wall portions 46 and 47 ride upon and fit snugly for approximately their entire length against the inner faces of the upturned portions 35 and 36 of the inturned run-ways or flanges 32 and 33.

When the extension arms 37 and 38 have thus been brought to the outer limits of the casing members 16 and 17, their inner end portions fit very snugly and securely within the outer end portions of the casing members 16 and 17. When in this position the casings and the extension arms have the effect of one continuous member curved downwardly from the center to conform to the shape of the shoulders of a coat.

It will be understood that the casings and the extension arms are so fitted together because of their various features which have been described, that slippage of the members one with the other is prevented. The flaring wall portions, the depending wall portions and the upturned run-way portions, together with the inturned bottom wall portions, are all so constructed and proportioned that the members of the hanger are maintained in any position desired until sufficient force be applied to move them.

When the garment hanger is not to be used and is to be put away or transported, it may be folded into a small compass as shown in Figure 5. In order to thus fold it, the extension arms 37 and 38 are moved into the casing members 16 and 17 until the inner edges of the extension arms come in contact with the pivot rods 27 and 28, respectively.

The extension arms are then rotated on the pivot rods 27 and 28 and are placed in an upright position, meeting, as is shown in Figure 5. The handle 23 remains in the upright position between the outwardly extended ears or lugs 21 and 22 which it has always maintained.

What I claim and desire to secure by Letters Patent of the United States is:

1. In a folding garment hanger, a central body frame, two casing members extending from opposite sides thereof and pivotally secured thereto, an extension arm slidably and frictionally engaged in each of said casing members, said extension arms being adapted to be held at any position desired within said casing members, each of the walls of said extension arms at the inner ends thereof being laterally divergent for a relatively short distance, the side walls of the extension arms each being provided with notches whereby said side walls of said inner portion of said extension arms have increased resiliency.

2. In a folding garment hanger, a central body frame, casing members extending from opposite sides thereof and pivotally secured thereto, an extension arm engaged in each of said casing members, said extension arms

having side walls, each of said side walls having a notch therein with a divergent wall portion at one side of the notch and a dependent wall portion at the other side of said notch, said extension arms being adapted to be held at any position desired within said casing members.

3. In a folding garment hanger, a central body frame, casing members extending from opposite sides thereof and pivotally secured thereto, an extension arm engaged in each of said casing members, said extension arms having side walls, each of said side walls having a notch therein with a divergent wall portion at one side of the notch and a dependent wall portion at the other side of said notch, said extension arms being adapted to be held at any position desired within said casing members, said divergent wall portions engaging the side walls of said casing members and the dependent wall portions, preventing the removal of said extension arms from said casing members.

In witness whereof I hereunto subscribe
25 my name this 26th day of June, A. D., 1928.

GEORGE F. McGILL.
